UNITED STATES PATENT OFFICE.

ANTHONY FRICKER, OF CLEVELAND, OHIO.

SNOWPLOW.

1,345,438.

Specification of Letters Patent.

Patented July 6, 1920.

Application filed December 23, 1918. Serial No. 268,034.

To all whom it may concern:

Be it known that I, ANTHONY FRICKER, a citizen of the United States, and resident of Cleveland, in the county of Cuyahoga and State of Ohio, have invented new and useful Improvements in Snowplows, of which the following is a description, reference being had to the accompanying drawings, which are a part of this specification.

10 The invention relates to snow plows and is fully described and explained in the specification and shown in the accompanying drawings in which:

15 Figure 1 is a side view of the device embodying the invention; Fig. 2 is a plan view thereof; Fig. 3 is a section taken on the line 3—3 of Fig. 1.

20 One of the features of this invention is the provision for attaching the plow to an automobile truck 4 or other motor driven vehicle and more particularly to the front axle 5 thereof.

25 The snow plow consists of three sets of plow blades hereinafter described, and supporting means for the blades.

30 The supporting means consists of a pair of beams 6 which are pivotally connected at their inner ends to the axle 5 by means of bearing members 7 mounted on said axle and secured to said beams in any suitable manner as by bolts 8 and said beams are supported at their outer ends upon runners 9 to which said beams are connected by means of vertically adjustable connections, 35 each consisting of a member 10 having a right and a left handed screw threaded end and carrying a hand wheel 11, one of the threaded ends engaging in a bore in a member 12 pivotally secured by a pin 13 to the beam and the other threaded end engaging in a bore in a base bracket 14 secured to the runner so that a rotation of the member 10 by the wheel 11 will cause movement of the member 12 toward or away from the bracket 14.

45 The base board 15 of the plow carries brackets 16 which are pivotally connected to the ends of the beams 6 by pins 17 and this base board is adapted to be tipped about this pivotal support and secured in different 50 positions of angular adjustment by means of vertically adjustable connections between the rear end of the board and said beams. Each connection consists of a member 18 having a right and a left handed screw threaded end and carrying a handwheel 19,

one of the threaded ends engaging in a bore in a member 20 pivotally secured to a pin 21 carried by the beam and the other threaded end engaging in a bore in a member 22 pivotally secured to a bracket 24, carried by the base board, by a pin 25.

55 The plow blades consist of a front set of blades 26, an intermediate set 27, and a rear set 28, all extending upwardly from the base board and braced by brace bars 29.

60 The front set of blades 26 consists of a pair of metal plates curved so as to deflect the snow outwardly to the sides of the road and separated from each other at their front 70 edges 30.

65 The intermediate set of blades 27 consists of a pair of metal plates curved so as to deflect the snow outwardly and separated from each other at their front edges 31, the front 75 portion of these blades being in the path of the snow passing between the blades 26.

70 The rear set of blades 28 consists of a pair of metal plates curved so as to deflect the snow outwardly and meeting each other at 80 their front edges 32, the front portion of these blades being in the path of snow passing between the blades 27.

75 From the foregoing description it will be observed that the snow covering the area in front of the plow is split up by contact with the various blades, that is, the front sides of the blades 26 deflect a portion of the snow to the sides, another portion is deflected to the sides between the blades 26 and 27 and another portion is deflected to the sides between the blades 27 and 28. Thus the snow is split up into a number of portions which are acted upon by the different plow sections so that the snow may be more readily 95 handled and with less power than with the usual type of scoop or single blade plow.

80 What I claim as my invention is:

85 1. A snow plow comprising a base board, a pair of front blades separated from each other and curved outwardly, an intermediate set of blades separated from each other and curved outwardly, the forward portions of this intermediate set being disposed in the path of the snow passing through the space 90 between the separated front blades, a rear set of blades meeting each other at the front edges, the forward portions of this rear set of blades being disposed in the path of the snow passing through the space 95 between the separated intermediate blades, and jack screw means adjustably supporting the 100

110

front and rear of the plow, whereby the height and the inclination thereof may be readily adjusted.

2. In a snow plow, the combination with 5 a vehicle, of a supporting member, a runner, means pivotally connecting the rear end of said member with the vehicle, a turn buckle jack screw having one end rigid with the runner and its other end pivoted to 10 the forward end of the supporting member, a snow plow including a base board, a

pivotal connection between the forward portion of the base board and the forward end of the supporting member, and means for adjustably supporting the rear portion of 15 the base board from said supporting members and including a jack screw turn buckle having one end pivotally connected with the supporting member and its other end pivotally connected with the base board. 20

In testimony whereof I affix my signature.
ANTHONY FRICKER.
